UNITED STATES PATENT OFFICE.

WILLIAM H. PASHLEY, OF NEW YORK, N. Y.

CASTING MACHINE.

Application filed January 4, 1922. Serial No. 527,015.

To all whom it may concern:

Be it known that I, WILLIAM H. PASHLEY, a citizen of the United States, residing at New York city, have invented new and useful Improvements in Casting Machines, of which the following is a specification.

This invention relates to improvements in casting machines and more particularly to horizontally disposed centrifugal casting machines.

One of the objects of the present invention is to provide a simple and practical casting machine of the above character which will be reliable and efficient in use and operation as well as one which may be inexpensively manufactured and assembled without sacrifice to the durability.

A further object is to provide a centrifugal casting machine which may be easily installed and wherein a plurality of castings may be made at the same time.

Other objects will be in part obvious and in part hereinafter pointed out.

In the accompanying drawings wherein is shown one of various possible modifications of the present invention,

Figure 1 is an elevational view partly in section of such parts of the apparatus as are necessary to understand the invention.

Figure 2 is a plan view, and,

Figure 3 is an end elevational view.

Referring to the drawing in detail, 5 indicates a main base support having laterally extending arms 7 at each side, which arms 35 are provided with secondary arms 8 positioned at right angles thereto for carrying feed spouts 10. These feed spouts are adapted to conduct the molten metal to the interior of horizontally disposed drums or cylinders 11 having threaded connections at 40 12 with a main shaft 13 mounted in bearings 14 and having a drive pulley 15 adapted to be connected by means of a belt 16 with any suitable source of power such as a motor 17 45 shown in Figures 2 and 3. A brake 18 actuated by means of handle 20 is adapted to coat with the shaft 13 to retard or stop its rotation after the metal has been cast. There is also provided a shield 21 about the open 50 ends of the casting drums for the purpose of protecting the workmen from outwardly splashing metal.

As the construction and operation of this device is well-known to those skilled in the art, a detailed statement is unnecessary. It 55 is sufficient to state that the molten metal is introduced into the rotating drums through the spouts 10 and after the metal has cooled the brake is actuated to bring the rotating drums to a stop. The drums 60 may then be unscrewed from their supports and new drums substituted at once whereby the casting apparatus may be made almost continuous.

The invention is of simple and practical 65 construction, may be easily manufactured and assembled, and is particularly designed to accomplish, among others, all of the objects and advantages herein set forth.

Without further analysis, the foregoing 70 will so fully reveal the gist of this invention that others can by applying current knowledge readily adapt it for various applications without omitting certain features that, from the standpoint of the prior art, fairly 75 constitute essential characteristics of the generic or specific aspects of this invention, and, therefore, such adaptations should and are intended to be comprehended within the meaning and range of equivalency of the 80 following claims.

What I claim is:—

1. In a casting apparatus, in combination, a shaft, means for rotating said shaft and casting drums detachably secured one at 85 each end of said shaft.

2. In a casting apparatus, in combination, a shaft, means for rotating said shaft, casting drums detachably secured to the ends of said shaft and feed spouts movably mounted with respect to said drums whereby they may be moved in and out with respect to the open ends thereof.

3. In a casting apparatus, in combination, a base, a main shaft carried thereby, a source 95 of power for rotating said shaft, means for retarding or stopping the rotation of said shaft, casting drums removably mounted at the ends of said shaft and means for conducting molten metal to the interior of said 100 drums.

Signed at Brooklyn, N. Y., this 10th day of October, 1921.

WILLIAM H. PASHLEY.
